UNITED STATES PATENT OFFICE

143,798

DESIGN FOR A PIN OR SIMILAR ARTICLE

William Crompton and Morris J. Laurie,
New York, N. Y.

Application July 11, 1945, Serial No. 120,642

Term of patent 7 years

(Cl. D45—19)

To all whom it may concern:

Be it known that we, William Crompton, a citizen of the United States, residing in New York city, county of New York, and State of New York, and Morris J. Laurie, a citizen of the United States, residing in New York city, county of New York, and State of New York, have invented a new, original, and ornamental Design for a Pin or Similar Article, of which the following is a specification, reference being had to the accompanying drawing, forming part thereof.

In the drawing:

Fig. 1 is a front elevational view of a pin showing our new design, and

Fig. 2 is a side elevational view thereof.

We claim:

The ornamental design for a pin or similar article, as shown.

WILLIAM CROMPTON.
MORRIS J. LAURIE.
